CLAMP CONNECTOR TOOL

Louis F. Heuer, Stanley J. Heuer, and
Donald C. Heuer, Portland, Oreg.

Application November 14, 1950, Serial No. 195,672

4 Claims. (Cl. 81—53)

1

This invention relates to electricians' or linemen's tools and, more particularly, to a tool for use with clamp type connectors commonly employed for interconnecting two electrical conductors.

Frequently it is desirable to make electrical connections to live conductors and which is more or less hazardous with tools heretofore available because of the fact that the two wires to be connected together must be held closely adjacent each other with one hand and the clamp connector assembled about the two conductors with the other hand and wrench then applied to the threaded screw element of the connector for fastening the same in place. Since the clamp connector unit is relatively small, it is difficult to manipulate the same with insulated gloves so that the electrician is inclined to remove his gloves and make the connection with bare hands thereby exposing himself to shock.

It is a general object of the present invention, therefore, to provide a new and improved linemen's tool for use in making electrical connections with clamp type fastener devices which is safe and easy to use.

More specifically, it is an object of the present invention to provide a linemen's tool comprising an insulated handle having a holder mounted thereon for removably receiving a clamp type connector unit, the tool including a wrench whereby the connector may be tightened after the same has been assembled around the electrical conductors to be connected together.

In accordance with the illustrated embodiment, the invention comprises an elongated, insulated handle having a head member rotatably mounted on one end of the handle, the head member defining a rectangular pocket adapted cooperatively to receive and hold therewithin a clamp type connector. A socket wrench element fixedly secured to the holder extends upwardly through the head member and into one end of the pocket, with the wrench socket so arranged as cooperatively to engage the head of the screw element of the clamp connector. In using the tool, the clamp connector is inserted into the holder pocket and the screw head engaged by the wrench socket. The clamp connector is then assembled about the electrical conductors to be fastened together and which may readily be accomplished by manipulation of the tool handle with a single hand. After the connector has been thus assembled, the handle may be twisted rotatably about its longitudinal axis to rotate the socket wrench while the head member is stationarily retained by the

2

electrical conductors thereby drawing the clamp unit tight. After the clamp unit has been tightened, the tool may readily be removed from the conductors and clamp unit all without necessitating direct contact by the hands with any electrically conductive part.

For a consideration of what is believed novel and inventive, attention is directed to the following description taken in connection with the accompanying drawing while the features of novelty will be pointed out with greater particularity in the appended claims.

In the drawing:

Fig. 1 is a front elevation illustrating the tool in accordance with the preferred embodiment thereof;

Fig. 2 is a side elevation of the tool as shown in Fig. 1;

Fig. 3 is a longitudinal, sectional view of the tool;

Fig. 4 is a top view of the tool;

Fig. 5 is an enlarged view in perspective illustrating a clamp connector unit for use with the tool;

Fig. 6 is a view illustrating the tool in use with one conductor assembled in the clamp connector held by the tool and about to be connected to a second conductor;

Fig. 7 is a front elevational view illustrating a further step of the usage of the tool and showing the clamp connector assembled about both conductors and in readiness for tightening;

Fig. 8 is a fragmentary, sectional view taken along the line 8—8 of Fig. 7;

Fig. 9 is a fragmentary, side elevational view showing the clamp connector in the tightened condition; and

Fig. 10 is a fragmentary side elevational view illustrating the step of removal of the tool from the clamp unit and conductors.

Referring now to the drawing, the invention comprises an elongated handle 10 of suitable insulating material, the handle being provided with relatively deep, longitudinal flutes 11 whereby a firm grip may be obtained upon the handle for effecting rotation thereof. Mounted in the upper end of the handle 10 is a head member 12 having a cylindrical base portion 13 extending downwardly into a cooperating, cylindrical recess 18 provided in the upper end of the handle 10. The head member 12 is rotatably movable relative to the handle 10 about an axis extending longitudinally of the handle. A rectangular pocket 14 is provided in the upper end of the head member 12, the pocket being open on one side of the tool, and

defined by the parallel sidewall or flange portions 15 and 16, an upper endwall 17, all of such walls extending outwardly at right angles from the rear wall formed by the head member proper. The pocket 14 is adapted cooperatively and relatively loosely to receive a clamp type connector of the type illustrated in greater detail in the perspective view of Fig. 5. Referring to this view, the clamp connector comprises a pair of relatively movable parallel jaw members 21 and 22 and a screw 23 extending through the rear portions of the jaw members, the screw 23 being provided with a hex head 24 whereby the jaw members may be tightened relatively together against a pair of conductors assembled within aligned facing grooves 25 provided in the jaw members 21 and 22. The upper end wall 17 of the head member 12 is provided with an opening 27 through which the upper end of the screw 23 may protrude, especially when the connector unit is tightened and as will be described more fully hereafter. The forward end of the wall portion 17 is preferably hook-shaped in the downward direction as indicated at 28 so as to fit relatively snugly over the curved upper surface of the upper jaw member 21 in order to snugly retain the clamp unit in place within the pocket once the latter is assembled therewithin.

A socket wrench 30 is fixedly secured relatively to the handle 10, the socket wrench being riveted as at 31 onto the upper end of a stem 32 extending coaxially of the handle and of the cylindrical portion 13 of the head member 12. The stem 32 extends through an opening provided in the endwall 33 of the cylindrical portion 13 of the head member while the lowermost end 34 of the stem 32 is fixedly embedded within the material forming the insulated handle 10. A compression coil spring 35 is provided about the stem 32 within the cylindrical portion 13 of the head member and between the collar 37 and the opposed shoulder defined by the endwall 33. The compression spring 35 resiliently biases the head member 12 downwardly toward the handle as the tool is viewed in the Figures 1 to 3. In the fully retracted position of the head member, the spacing provided between the uppermost end of the socket wrench element 30 and the lower surface of the upper endwall 17 is somewhat less than the length of the clamp connector.

In using the tool, the jaws of the clamp connector unit are first opened wide as shown in Fig. 8 although the jaws may be separated to the desired extent after the connector unit has been assembled within the pocket 14 of the head member. To insert the clamp connector unit into the pocket, the head member 12 of the tool is first pushed outwardly of the handle against the bias of the spring 35 by holding the handle in one hand and pushing with the thumb against the outwardly extending flange portion 41 of the head member next adjacent the upper end of the handle 10. The position of the handle relative to the head member in the extended position is indicated by the dotted lines 42 in Fig. 2. This increases the distance between the endwall 17 and the socket wrench 30 to enable easy insertion of the connector unit. After the clamp connector unit has been inserted into the tool pocket, the flange portion 41 may be released whereupon the head member will be drawn downwardly toward the handle by the spring 35 and the hex head 24 of the connector unit screw inserted cooperatively into the socket 43 of the wrench. By holding the head member 12 relatively stationary with one hand,

the handle 10 may be rotated for opening the jaws of the clamp connector to the extent desired, or as shown in Fig. 8. The clamp connector is stationarily retained within pocket 14 in the head member during this operation, permitting free relative rotational movement of the screw 23.

Referring now to Fig. 6, the end of one conductor 45 is first inserted as shown into the groove of the lower jaw member of the clamp connector, the outer end portion 46 of the conductor being preferably bent downwardly as shown to minimize the tendency for the conductor 45 to slip out of the connector groove as the conductor 45 is carried upwardly toward the line conductor 47 to which it is to be attached. In Fig. 7 the tool is shown in position with the upper jaw of the clamp connector unit hooked over the upper surface of the line conductor 47 to which the conductor 45 is to be attached. The handle 10 may now be rotated to cause tightening of the connector screw 23 while pulling down slightly on the handle at the same time in order that the head member 12 of the tool will remain stationary during rotation of the handle. It is to be understood that the line conductor 47 to which connection is to be made will normally be substantially rigidly supported so that a downward pull may be exerted thereagainst by the handle 10 without causing undue reflection thereof from the supported position. The spring 35 is purposely made relatively stiff so that a downward pull exerted upon the handle for the purpose of retaining the conductor 47 seated within the groove of the upper connector jaw member 21 will not result in disengagement of the socket wrench from the head of the connector screw 23. Attention is also directed to the fact that the edges of the sidewall portions 15 and 16 of the head member 12 are relatively wide and, moreover, extend upwardly along each of the opposite sides of the connector unit to a position relatively closely adjacent conductor 47 positioned within the groove of the upper jaw 21. Rotational movement of the head member 12, upon rotation of the handle 10, when the tool is manipulated by one hand, is prevented by engagement of the conductor 47 at two relatively widely spaced points, the first being against the outer edge of one or the other sidewall portions such as indicated at 50 in Fig. 7, the other point being indicated at 51, the side of the connector jaw member opposite the point 50. After the connector screw 23 has been tightened and two conductors 45 and 47 clamped securely together, the tool may then be removed from the conductor assembly by pulling down forcibly upon the handle 10, so as to withdraw the socket wrench from the connector screw head 24 and then swinging the tool outwardly in an arcuate direction as indicated by the arrow 52 in Fig. 10. After the lower end of the connector is removed from the holder pocket formed within the head member 12 and clear of the socket wrench element 30, the tool may then be lifted upwardly so as to clear the upper end of the connector element.

As shown in Fig. 9, as the connector jaw members are tightened relatively together with the conductors between the jaw members, the upper end of the screw 23 may protrude freely from the upper end of the head member through the hole 27 provided therewithin as previously described.

It will be obvious that the handle 10 may be made of any suitable length. Only a relatively short handle is shown in the drawings but for use in making connections to conductors at consid-

erable heights, the tool may be mounted by means of a suitable adapter on the end of a pole.

It will be seen from the description given, that by using the tool of the present invention, a tap connection may readily be made to a live conductor without requiring the electrician to hold, or touch directly with his hands, either of the conductors, the clamp connector unit, or any conductive part of the tool itself. The tool, therefore, eliminates the hazard formerly inherent in making connections of this type, and also simplifies the work which was more or less awkward to perform with conventional tools.

Having described the invention in what is considered to be a preferred embodiment, it is desired that it be understood that the specific details shown are merely illustrative and that the invention may be carried out in other ways.

We claim:

1. A clamp connector tool comprising an elongated handle, an elongated head member mounted on one end of said handle and extending longitudinally therefrom, said head member including a pair of spaced apart parallel side wall flanges and an outer endwall flange defining a rectangular pocket for cooperatively receiving and retaining a connector unit including a screw element and with said screw element extending in the longitudinal direction of said handle and with the head of said screw element facing the adjacent end of said handle, a socket wrench, a stem fixedly secured to said handle and extending into said head member, said socket wrench being fixedly secured to the outer end of said stem and extending into said pocket and facing said endwall, said socket wrench being adapted for cooperatively engaging the head of said screw element, said head member being slidably and rotatably mounted upon said stem between said socket wrench and said handle and a spring operatively arranged between said head member and said handle for resiliently biasing said head member toward said handle.

2. A clamp connector tool comprising a handle, a head member including a cylindrical base portion, a cylindrical recess extending into one end of said handle for cooperatively receiving the cylindrical base portion of said head member, said cylindrical portion being freely rotatable within said recess, the outer end portion of said head member including a pair of spaced-apart parallel side wall flanges and an outer end wall flange defining a rectangular pocket for cooperatively receiving and retaining a connector unit including a screw element and with said screw element extending in the longitudinal direction of said handle and with the head of said screw element facing the adjacent end of said handle, a stem fixedly secured to said handle and extending coaxially through said recess and said cylindrical portion, a socket wrench secured to the outer end of said stem and adapted cooperatively to engage the head of said screw element, said head member being longitudinally slidably upon said stem, a compression spring arranged about said stem within said cylindrical base portion, the opposite ends of said spring bearing against opposing shoulders provided respectively upon said stem and upon said cylindrical base portion whereby said head member is biased resiliently in the direction toward said handle.

3. A clamp connector tool comprising a handle, a head member including a cylindrical base portion, a cylindrical recess extending into one end of said handle for cooperatively receiving the cylindrical base portion of said head member, said cylindrical portion being freely rotatable within said recess, the outer end portion of said head member including a pair of spaced-apart parallel side wall flanges and an outer end wall flange defining a rectangular pocket for cooperatively receiving and retaining a connector unit including a screw element and with said screw element extending in the longitudinal direction of said handle and with the head of said screw element facing the adjacent end of said handle, a stem fixedly secured to said handle and extending coaxially through said recess and said cylindrical portion, a socket wrench secured to the outer end of said stem and adapted cooperatively to engage the head of said screw element, said head member being longitudinally slidably upon said stem, a compression spring arranged about said stem within said cylindrical base portion, the opposite ends of said spring bearing against opposing shoulders provided respectively upon said stem and upon said cylindrical base portion whereby said head member is biased resiliently in the direction toward said handle, said head member including a flange portion extending laterally upwardly beyond the adjacent edge of said handle and defining an abutment for manual engagement for shifting said head member longitudinally of said stem against the force of said spring.

4. A clamp connector tool comprising a handle, a head member including a cylindrical base portion, a cylindrical recess extending into one end of said handle for cooperatively receiving the cylindrical base portion of said head member, said cylindrical base portion being freely rotatable within said recess, the outer end of said head member including a pair of spaced-apart parallel side wall flanges and an outer end wall flange defining a rectangular pocket for cooperatively receiving and retaining a connector unit including a screw element and with said screw element extending in the longitudinal direction of said handle and with the head of said screw element facing the adjacent end of said handle, a stem fixedly secured to said handle and extending coaxially through said recess and said cylindrical portion, a socket wrench secured at the outer end of said stem and adapted to engage cooperatively the head of said screw element, and means resiliently biasing said head member toward said handle whereby said socket wrench is urged into said pocket to engage said screw element head.
